(57) **CLAIM**

The ornamental design for a slotwall board system, as shown and described.

DESCRIPTION

FIG. 1 is a front perspective view of the slotwall board system of the present invention showing my new design; FIG. 2 is an end view thereof with the phantom lines depicting solely environmental structure and forming no part of the claimed design;

FIG. 3 is a top plan view thereof;

FIG. 4 is front elevational view thereof;

FIG. 5 is a bottom plan view thereof; and,

FIG. 6 a rear elevational view thereof.
